UNITED STATES PATENT OFFICE

92,047

DESIGN FOR A TIRE

Sheldon P. Thacher, Detroit, Mich., assignor to
United States Tire Company, Incorporated, a
corporation of Indiana

Application June 30, 1933, Serial No. 48,599

Term of patent 14 years

To all whom it may concern:

Be it known that I, SHELDON P. THACHER, a citizen of the United States, residing at Detroit, county of Wayne, and State of Michigan, have invented a new, original, and ornamental Design for a Tire, of which the following is a specification, reference being had to the accompanying drawing, forming part thereof, wherein:

Fig. 1 is a side view of a tire side wall embodying the design;

Fig. 2 is a cross-section of a portion of the tire side wall taken along the section line II-II of Fig. 1;

Fig. 3 is a cross-sectional view of one of the buttresses on the tire side wall taken along the section line III-III of Fig. 1, and

Fig. 4 is a perspective view of a tire with side wall portions in full lines showing my new design.

I claim:

The ornamental design for a tire, as shown.

Signed at Detroit, in the county of Wayne and State of Michigan, this 22nd day of June, 1933.

SHELDON P. THACHER.
